UNITED STATES PATENT OFFICE.

GEORGE BENNISON GREEN, OF NEW YORK, N. Y., ASSIGNOR TO FRANK BACH, OF SAME PLACE.

DESIGN FOR A HASSOCK.

SPECIFICATION forming part of Design No. 30,509, dated April 4, 1899.

Application filed February 21, 1899. Serial No. 706,416. Term of patent 14 years.

To all whom it may concern:

Be it known that I, GEORGE BENNISON GREEN, a citizen of the United States, residing at New York, (Brooklyn,) in the county of Kings and State of New York, have invented and produced a certain new and original Design for Hassocks; and I do declare the following to be a full, clear, and exact description of the invention, such as will enable others skilled in the art to which it appertains to make and use the same.

The invention has relation to a new and original design for hassocks; and it consists in a hassock of the configuration and ornamentation shown in the accompanying drawings, in which—

Figure 1 is a side elevation of the invention, and Fig. 2 is a top plan view.

The hassock consists of a smooth cylindrical body portion 1, having at its base an

annular ring 2 and at its upper edge a similar ring 3, from which extends in a zigzag manner a colored or striped cord 4, laced through ornamental rosettes 5.

6 denotes bows of ribbon, and 7 a tufted crown composed of differently-colored segmental sections.

8 denotes a loop connected centrally to the tufted crown.

What I claim, and desire to secure by Design Letters Patent of the United States, is—

The design for a hassock as herein shown and described.

In testimony whereof I have hereunto set my hand in presence of two subscribing witnesses.

G. BENNISON GREEN.

Witnesses:

JOHN L. SPENCE,

Wm. E. A. SMITH.
